Primary Examiner — Darcey E Gottschalk*(74) Attorney, Agent, or Firm* — Moore, Ingram, Johnson & Steele, LLP(57) **CLAIM**

The ornamental design for a utensil, as shown and described.

DESCRIPTION

FIG. 1 is a perspective view of a utensil in accordance with the patent design;

FIG. 2 is a perspective view of a FIG. 1;

FIG. 3 is a view of the front of the utensil of FIG. 1;

FIG. 4 is a view of the back of the utensil of FIG. 1;

FIG. 5 is a view of the right side of the utensil of FIG. 1;

FIG. 6 is a view of the left side of the utensil of FIG. 1;

FIG. 7 is a top view of the utensil of FIG. 1; and,

FIG. 8 is a bottom view of the utensil of FIG. 1.

The forked utensil of the present application is a kitchen utensil intended to be used for dipping food, such as strawberries, into liquid, melted cheese, melted chocolate. The handle of the utensil is indented slightly to prevent slippage.

1 Claim, 3 Drawing Sheets(56)
